UNITED STATES PATENT OFFICE.

JOHN K. RAUGSTAD, OF GRASS RANGE, MONTANA.

DESIGN FOR A SMOKING SET OR SIMILAR ARTICLE.

Application filed November 23, 1926. Serial No. 19,822. Term of patent 7 years.

To all whom it may concern:

Be it known that I, JOHN K. RAUGSTAD, a citizen of the United States, residing at Grass Range, in the county of Fergus and State of Montana, have invented a new, original, and ornamental Design for a Smoking Set or Similar Article, of which the following is a specification, reference being had to the accompanying drawing, forming part thereof.

Fig. 2 is a front end view, and

Fig. 3 is a rear end view of a smoking set or similar article embodying my design.

I claim:

The ornamental design for a smoking set or similar article, as shown.

JOHN K. RAUGSTAD.
